UNITED STATES PATENT OFFICE.

STIRLING B. HILL, CLIMIE E. HILL, AND WILLIAM R. HILL, OF SEATTLE, WASHINGTON.

HYDRAULIC RAM.

1,016,409.

Specification of Letters Patent.

Patented Feb. 6, 1912.

Application filed February 11, 1911, Serial No. 608,077. Renewed December 23, 1911. Serial No. 667,548.

To all whom it may concern:

Be it known that we, STIRLING B. HILL, CLIMIE E. HILL, and WILLIAM R. HILL, citizens of the United States, residing at 5 Seattle, in the county of King and State of Washington, have invented certain new and useful Improvements in Hydraulic Rams, of which the following is a specification.

10 Our invention relates to hydraulic rams.

An important object of this invention is to provide a valve in a hydraulic ram which with a small weight and movement will produce a maximum area for the passage of 15 water.

A further object of this invention is to furnish valves in the hydraulic ram so shaped that the pressure thereon will be as nearly as practicable, balanced thus greatly 20 reducing the jar of closing.

A further object of this invention is to provide a hydraulic ram which is efficient, expeditious and continuous in its operation.

A further object of this invention is to 25 provide a hydraulic ram of simple and compact construction, having its waste valve discharging downwardly so that the water does not go upwardly to fall back upon the ram.

30 A further object of this invention is to provide a hydraulic ram comprising valves so constructed that the least amount of resistance is offered to the water when passing therethrough.

35 Other objects and advantages of this invention will be apparent during the course of the following description.

In the accompanying drawings forming a part of this specification, and in which like 40 numerals are employed to designate like parts throughout the same, Figure 1 is a central vertical sectional view taken through our improved hydraulic ram, Fig. 2 is a similar view taken through a slightly different form of ram, and, Fig. 3 is a similar view taken through a third different form of ram.

In the drawings wherein is illustrated a preferred embodiment of our invention, attention being called to Fig. 1, the numeral 1 designates a preferably approximately cylindrical casing, provided at its upper and lower ends with flanged nipples 2 and 3. The casing 1 is further provided with a 55 laterally extending nipple 4, having suitable connection with a coupling 5, which in turn

is connected with a drive pipe 6. The lower nipple 3 is designed for connection with a waste pipe (not shown). Disposed above the nipple 2 is a pressure storage tank, which 60 may preferably be formed in two sections 7 and 8, secured together by any suitable means. The lower tank section 8 is disposed upon and suitably secured to the flanged nipple 2. The lower end of the tank section 65 8 is formed open, as shown, whereby communication may be established between the casing 1 and said storage tank. The tank section 8 is provided with a discharge pipe 9, adapted to conduct the fluid under pressure to the device which is to be operated thereby. The tank section 8 is provided preferably at a point diametrically with relation to the pipe 9 with a man-hole 10, which is normally closed by a head 11. This 70 head engages packing 12 disposed between the head 11 and the tank section 8, as shown. The head 11 has rigid connection with a stem 13, which is slidably mounted through a spider 14 formed upon the tank section 8. 80 The stem 13 is screw-threaded for engagement with a nut 15, by the means of which the head 11 may be clamped in its closed position.

The passage of water through the nipple 85 3 is controlled by a waste valve structure, comprising a plurality of annular valves 16 and 17. These valves are formed curved in cross-section, as shown, to conduct the water by the same with the least possible amount 90 of friction. The valves 16 and 17 have their lower ends adapted to be moved into and out of engagement with valve seats 18 and 19, respectively. These valve seats comprise packing rings 20. The annular valve seat 95 19 is positioned upon the nipple 3 and attached thereto by any suitable means. The annular valve seats 18 and 19 are rigidly connected by preferably diametrically arranged sections of material or webs 21, which 100 extend upwardly for engagement with a circular valve seat 22. The upper ends of the annular valves 16 and 17 are adapted to engage the valve seats 22 and 18, respectively, said annular valves being provided 105 with packing rings 23 and 24 to make these engagements air tight. The circular valve seat 22 has rigid connection with a vertically disposed stem 25, upon which is slidably mounted a collar 26, having depending preferably diametrically arranged rods 27 connected therewith. These rods are suitably

connected with the annular valves 16 and 17, as shown at 28. The upward movement of the collar 26 is limited by a nut 29 engaging the upper screw threaded portion of the 5 stem 25, said nut 29 being locked in adjustment at different positions by a second nut 30. A section of packing 31 is disposed between the collar 26 and the nut 29 and secured to said nut by any suitable means. A 10 section of packing 32 is slidably connected with the lower end of the collar 26. A lock nut 33 is screw threaded onto bolt 25 and engages the circular valve seat 22 to hold 25 firmly in place.

15 The casing 1 is provided opposite the nipple 4 with an opening 34, adjacent which is disposed an auxiliary casing 35, having flanges 36 and 37, as shown. The flange 36 extends within the opening 34 while the 20 flange 37 is rigidly connected with the casing 1 by any suitable means. Disposed within the auxiliary casing 35 is a leaf-spring 38, formed of a plurality of spring-leaves 39, carrying plates 40, which are held 25 together by clamps 41. The lower plate 40 is provided with a recess for receiving the upper end of a bolt 42, operating through a screw-threaded opening formed in the casing 35. The outer end of the leaf-spring 30 38 is disposed below a shoulder 43 formed in the casing 35, while the inner end of this leaf-spring is provided with an opening for receiving the stem 25. The leaf-spring 38 is so tensioned that the same tends to hold 35 the annular valves 16 and 17 in their open or raised position. By rotating the bolt 42 the tension of the leaf-spring 38 may be varied. The auxiliary casing 35 is provided with a discharge opening 45, which is normally closed by a valve 46, having rigid 40 connection with a stem 47, which in turn operates through an opening formed in a spider 48. The stem 47 is screw-threaded for receiving a nut 49, whereby the valve 45 45 may be locked in its closed position. After the nut 49 has been moved away from the spider 48, the valve 46 may be unseated by oscillating a lever 50, carried by a link 51, which is pivotally connected with the 50 auxiliary casing 35, as shown at 52.

The passage of water into the storage tank from the casing 1 is controlled by a discharge valve structure, comprising spaced superposed circular and annular valves 53 and 54, respectively. These valves are 55 adapted to engage and disengage annular valve seats 55 and 56, provided with packing 57, as shown. The lower valve seat 56 is disposed within and suitably secured to 60 the nipple 2. The valve seats 55 and 56 are rigidly connected in their spaced relation by preferably diametrically arranged sections of material or webs 58, to the upper ends of which is rigidly connected a 65 vertically disposed stem 59. This stem 59

serves as a guide for the vertically movable valve 53. The annular valve 54 is connected with the valve 53 by means of preferably diametrically arranged rods 60. The valve 53 is normally held in its lowermost 70 position by a compressible coil spring 61, which is engaged by a nut 62, which in turn is clamped in adjustment in different positions by a second nut 63. The casing 1 is provided near its upper end with an opening 64 formed therethrough, which is adapted to supply air within said casing. A check valve (not shown) is to be provided to allow the air to enter the casing 1 but to close upon a reverse movement of the air. 80

In the operation of this form of ram, assuming that the waste valve structure is in its open position, as shown in Fig. 1, the water will begin to run in the drive pipe 6 and discharge through the waste valve structure. When the flow of the water increases sufficiently in velocity, the same by impinging against the annular valves 16 and 17 causes the same to be seated and the flow of water through the nipple 3 cut off. When the water is flowing through the nipple 3, as above described, a partial vacuum is created within the casing 1, whereby air is drawn into this casing through the opening 64. As soon as the waste valve structure 90 is closed the pressure increases in the casing 1 and closes the check valve (not shown) controlling the opening 64. The water under pressure and the small amount of air which entered the valve 64 now rises in the 100 casing 1 and by opening or unseating the valves 53 and 54, enters the storage pressure tank. The operation continues until the energy in the moving column of water in the drive pipe is dissipated at which instant the flow of water through 53 and 54 stops and the valves close. The pressure continues to rapidly fall in the casing 1 whereby the spring 38 unseats the valves 16 and 17 and the operation as described 110 above is repeated. The object of having a small amount of air enter at each stroke is to maintain the air supply in the storage pressure tank as this would be otherwise slowly dissolved by the flowing water. The 115 valve 45 is employed when starting the device, the same being opened or unseated to reduce the pressure, within the casing 1.

When starting the device, the valve 45 is unseated, whereby the water may more 120 freely pass from the casing 1 and hence the velocity of the water in the drive pipe will be materially increased. The valve 45 may also be employed to quicken the action of the device, for assuming that the water in 125 the drive pipe has gained in velocity sufficiently to seat or close the waste valve structure, such velocity of the water will then begin to decrease. The waste valve structure is retained seated by the pressure in 130

the casing 1, so when the valve 45 is unseated this pressure is reduced which causes the waste valve structure to be at once unseated and hence allow the water in the drive pipe 6 to continue its movement and increase in velocity. It will thus be seen that by unseating the valve 45 the stroke of the hydraulic ram may be shortened and made quicker.

Referring now to Fig. 2, the form of the hydraulic ram shown therein, comprises a casing 65, provided at its upper and lower ends with flanged nipples 66 and 67. The casing 65 is provided upon one side thereof with a flanged nipple 68, for connection with a drive pipe (not shown). The lower nipple 67 has suitable connection with a waste pipe 69. Disposed above the casing 65 is a pressure storage tank 70, having its open lower end provided with an annular flange 71, which is suitably connected with the flanged nipple 66. The flow of water from the casing 65 into the waste pipe 69 is controlled by a waste valve structure, comprising spaced superposed circular and annular valves 72, 73 and 74. These valves are disposed in superposed relation and are connected by pairs of preferably diametrically arranged rods 75. The valves 72, 73 and 74 coöperate with spaced superposed annular valve seats 76, 77 and 78, having their lower ends concaved, as shown. These valve seats are rigidly connected by sections of material or webs 79, which are preferably diametrically arranged. The lower valve seat 78 is connected with the nipple 67, by means of screws 80 or the like. The valve seats 76, 77 and 78 carry packing rings 81 upon their upper ends, as shown. The annular valves 73 and 74 carry packing rings 82 upon their upper ends. The webs 79 have their adjacent upper ends provided with an opening formed therethrough for slidably receiving a reduced end 83 of a vertically disposed stem 84. This stem has screw threaded engagement with the valve 72, as shown. The stem 84 is slidably mounted through an opening formed through the inner end of a horizontal arm 85. This arm extends with in an auxiliary casing 86 formed upon one side of the casing 65. The arm 85 is provided intermediate its ends with a cylindrical opening formed therethrough for rotatably receiving a reduced cylindrical portion 86' of an adjusting bolt 87. This bolt carries a nut 88. The bolt 87 operates through a screw-threaded opening formed through the auxiliary casing 86. The arm 85 is engaged by a pair of clamping bolts 89, operating in screw-threaded openings formed through the auxiliary casing 86. The upper end of the stem 84 is screw-threaded for engagement with a cap 90, which engages a compressible coil spring 91, having engagement with a cap 92 surround-

ing stem 84 and disposed upon the horizontal arm 85. The function of the spring 91 is to normally hold the valves 72, 73 and 74 in their unseated positions. By adjusting the arm 85 the tension of the coil spring 91 may be varied. The discharge of water from the casing 65 into the pressure storage tank 70 is controlled by a discharge valve structure, comprising spaced superposed circular and annular valves 93, 94 and 95. These valves are rigidly connected by means of pairs of preferably diametrically arranged rods 96, as shown. These valves coöperate with spaced superposed annular valve seats 97, 98 and 99, which are rigidly connected by sections of material or webs 100, disposed preferably in diametrical relation. The lower valve seat 99 is disposed within and has suitable connection with the upper nipple 66. The upper ends of the webs 100 are connected with a cylinder 101, having an opening 102 formed through its lower end, for receiving a reduced extension 103 formed upon the stem 84. The cylinder 101 carries packing 104 upon the lower end thereof. The annular valves 94 and 95 carry packing rings 105 and 106 at their upper and lower ends, as shown. The circular valve 93 carries packing 107 at its lower end. The circular valve 93 is slidably mounted upon a vertically disposed stem 108, having screw-threaded engagement with the cylinder 101. The circular valve 93 is engaged by a socket 109, receiving one end of a compressible coil spring 110, having its upper end disposed within the socket 111. The upper end of the stem 108 is screw-threaded for the reception of nuts 112. The lower end of the casing 65 is provided with a spigot 113, which may be operated to discharge the water from said casing. The casing 65 is provided at its upper end with an air inlet 114, controlled by a check valve 115 and a cut-off valve 116. It is to be understood that all three forms of our invention are provided with the co-operating check valve and cut-off valve. The storage tank 70 is provided with a discharge opening 117, which leads into a pipe (not shown) for conducting the fluid to any desired place.

In the operation of this form of our invention, when the valve structures are in the positions shown in Fig. 2, the water from the drive pipe is being discharged into the storage tank 70. As soon as the water decreases in velocity sufficiently, the pressure in the casing 65 is reduced and the spring 91 will open the waste valve structure. The discharge valve structure is closed prior to the opening of the waste valve structure. The column of water now increases in velocity and impinges against the circular valve 72 to close the waste valve structure. The operation is then repeated. Air is drawn into the casing 65 through the

opening 114, for a purpose as explained in connection with Fig. 1.

In Fig. 3, we have shown a third different form of hydraulic ram, the same comprising a casing 118, provided at its upper and lower ends with flanged nipples 119 and 120. The casing 118 is provided upon one side thereof with a flanged nipple 121 for connection with a drive pipe (not shown).
10 The lower nipple 120 has suitable connection with a waste pipe 122. Disposed above the upper nipple 119 is a pressure storage tank 123, having its lower open end provided with an annular flange 124, which is disposed upon and suitably connected with said upper nipple. The tank 123 is provided with a discharge opening 125, which leads into a pipe (not shown) having communication with the device to be operated.
15 The casing 118 is provided near its lower end with a spigot 126, whereby water may be discharged from the casing 118. The casing 118 is further provided at its upper end with an air inlet 126', which is controlled by a check valve and cut-off valve, in the same manner as described in connection with Fig. 2. The passage of water through the waste pipe 122 is controlled by a waste valve structure, comprising a plurality of spaced superposed circular and annular valves 127, 128 and 129. The annular valves 128 and 129 carry packing rings 130, secured upon the upper ends thereof. The annular valves are rigidly connected with the circular valve 127 by pairs of preferably diametrically arranged rods 131. The valves coöperate with spaced superposed annular valve seats 132, 133 and 134, which are rigidly connected by diametrically arranged sections of material or webs 135. The valve seat 134 is disposed within and connected with the lower nipple 120 by means of screws 136. The annular valve seats have packing rings 137 suitably secured to the upper ends thereof. The webs 135 extend downwardly for connection with a tube section 138, within which is mounted a tube 139. A vertically disposed stem 140 extends through an opening formed through the circular valve 127 and is disposed within the tubes 138 and 139. A compressible coil spring 141 surrounds the stem 140 and has engagement with the valve 127 below the same. This spring has its lower end disposed within the tube 139 and engages a cap 142, which is held in place by a nut 143. The stem 140 is held in its requisite position by a horizontal arm 144, said stem being provided with nuts 145 to clamp the inner end of the arm upon opposite sides thereof. The arm 144 is supported in a like manner to the corresponding arm shown and described in connection with Fig. 2. The function of the spring 141 is to retain
20
25
30
35
40
45
50

60
65 the waste valve structure open. The up-

ward movement of the valve 127 is opposed by compressible coil springs 146, carried by vertically disposed bolts 147, which extend through suitable openings formed in said valve 127 and are rigidly connected with the uppermost annular valve seat, as shown. The discharge of the water into the storage tank 123 from the casing 118, is controlled by a discharge valve structure, comprising an inverted cup-shaped receptacle 148, having its lower open end disposed within and suitably connected with the upper nipple 119. This casing is provided upon its top and side walls with a plurality of openings 149 formed therethrough. Each of these openings has a spider 150 disposed therein and suitably connected with said receptacle. These spiders have screw-threaded engagement with bolts 151, which carry curved plates 152. Disposed between the curved plate and the spider is a suitably flexible valve 153. Each of the valves 153 is capable of allowing the water to flow through the opening 149 into the tank 123, but such valve will close upon a reverse movement of the water, the curved plate being provided with openings 154 formed therethrough.

The operation of this form of our invention is very similar to the operation recited in connection with Figs. 1 and 2 and therefore need not be again given. 95

We wish it understood that the forms of our invention herewith shown and described, are to be taken as preferred examples of the same, and that certain changes in the shapes, sizes, and arrangements of parts may be resorted to without departing from the spirit of the invention or the scope of the subjoined claims.

Having thus fully described our invention, we claim:—

1. In a hydraulic ram, a casing provided with upper and lower oppositely arranged discharge and waste openings, a valve for controlling the discharge opening, a valve 110 for controlling the waste opening, a spring tending to unseat the second named valve, and means disposed in the line of flow of supply and adapted for discharging material from said casing in addition to the discharge and waste openings for the purpose 115 of starting the ram.

2. In a hydraulic ram, a casing provided with discharge and waste openings, valves for controlling the passage of material through such openings, and a valve disposed in the line of flow of supply and adapted when unseated to discharge material from said casing in addition to the discharge passing through the two named openings. 120

3. In a hydraulic ram, a casing provided with discharge and waste openings, a valve for controlling the discharge opening, a valve for controlling the waste opening,

- 5 said casing being provided with a third opening in addition to the two named openings and disposed in the line of flow of supply, a valve for controlling the third named opening, and manually operated means to move the last named valve.
- 10 4. In a hydraulic ram, a casing provided with discharge and waste openings, a valve for controlling the discharge opening, a valve for controlling the waste opening, an auxiliary casing having communication and connected with said casing, a leaf-spring disposed within the auxiliary casing and extending into the first named casing
- 15 for engagement with the waste valve for normally holding the same unseated, and movable means engaging the wall of the auxiliary casing for changing the tension of the leaf-spring.
- 20 5. In a hydraulic ram, a casing provided with discharge and waste openings, a valve for controlling the discharge opening, a valve for controlling the waste opening, an

auxiliary casing having communication and connected with said casing, said auxiliary casing being provided internally thereof with a shoulder, a leaf-spring disposed within the auxiliary casing and extending therefrom to be positioned in the first named casing to have connection with the waste valve, said leaf-spring having one end thereof disposed below and in engagement with said shoulder, and a bolt longitudinally movably mounted through the auxiliary casing to engage the leaf-spring for changing the tension thereof upon the rotation of said bolt.

25 30 In testimony whereof we affix our signatures in presence of two witnesses.
